UNITED STATES PATENT OFFICE

124,896

DESIGN FOR A SHOE OR SIMILAR ARTICLE

Jacob Fein, New York, N. Y.

Application March 20, 1940, Serial No. 91,093

Term of patent 3½ years

To all whom it may concern:

Be it known that I, Jacob Fein, a citizen of the United States and a resident of the city of New York, county of Bronx, State of New York, have invented a new, original, and ornamental Design for a Shoe or Similar Article, of which the following is a specification.

Reference is had to the accompanying drawing, forming a part thereof, in which Fig. 1 is a perspective view of a shoe embodying my new design, and Fig. 2 is a side view thereof.

The characteristic feature of the design resides in the transparent shank member.

I claim:

The ornamental design for a shoe or similar article, substantially as shown and described.

JACOB FEIN.
